(57) **CLAIM**

We claim the ornamental design for a vane for use in coverings for architectural openings, as shown and described.

DESCRIPTION

FIG. 1 is an isometric view of the present invention. FIG. 2 is a top plan view of the vane of FIG. 1, with a bottom plan view being a mirror image thereof; and, FIG. 3 is a right end elevation of the vane of FIG. 1, with a left end elevation being a mirror image thereof.
